UNITED STATES PATENT OFFICE.

SAMUEL BARROW, DAVID BARROW, AND JACOB BARROW, OF INDIANAPOLIS, INDIANA.

ROTARY ENGINE OR PUMP.

SPECIFICATION forming part of Letters Patent No. 231,520, dated August 24, 1880.

Application filed February 11, 1880.

To all whom it may concern:

Be it known that we, SAMUEL BARROW, DAVID BARROW, and JACOB BARROW, of Indianapolis, in the county of Marion and State of Indiana, have invented a new and useful Improvement in Rotary Engines and Pumps, of which the following is a specification.

Our invention relates to rotary engines, water-motors, or pumps wherein a wheel is fitted eccentrically in an elliptically-shaped chamber or steam and water way, and fitted with two pistons, which are projected from the periphery of the wheel and travel in an elliptical path.

Our invention consists in certain novel details of construction of the engine, which will be particularly described hereinafter with reference to the accompanying drawings, forming part of this specification.

In the drawings, Figure 1 is a side elevation of the engine. Fig. 2 is a vertical section on line $x x$ of Fig. 1. Fig. 3 is a vertical section at right angles to the axis of the wheel on line $y y$ of Fig. 2. Fig. 4 is a side view of the wheel. Fig. 5 is a view of the wheel at the reverse side and partially in section. Figs. 6, 7, and 8 are diagrams illustrating the elliptical movement of the pistons. Figs. 9 and 10 are detail views.

Similar letters of reference indicate corresponding parts.

A is the case of the engine, formed with an elliptical interior, a , and fitted with side plates, $b c$, between which is the wheel B, hung eccentrically to the interior a . The wheel B is sustained at one side by a hollow trunnion or axle, d , that extends through the plate to the spider c' , that is attached upon the plate c , and at the opposite side by the shaft e , that is connected to the wheel and extends through plate b and through a box in the spider f . The shaft e is formed at its outer end with a coupling for taking power from the engine, or for driving the wheel B by a separate motor when the apparatus is used as a pump.

Upon the axle d and shaft e are packing glands or rings g , which enter stuffing-boxes formed in plates $b c$, and screws g' , tapped in the spiders c' and f , serve to press the rings g upon the packing and pack the axle and shaft tightly. The side plates of wheel B are grooved

to receive metal packing-segments h , which are pressed outward against the plates $b c$ by spiral springs i , placed in mortises behind the segments h , as shown in the detail, Fig. 9. This construction furnishes complete and durable packing.

At the upper part of interior a the case A is fitted with a metal packing-segment, k , that is pressed down on wheel B by a spiral spring, l , as shown in Fig. 2. At opposite sides of k are ports $m m'$, connecting with grooves $n n'$ in the sides of interior a , and between the ports $m m'$ is an exhaust-port, o , communicating with the exhaust-pipe p .

The wheel B consists of a ring portion, r , (shown most clearly in Figs. 4 and 5,) that is formed with radial mortises, which serve as boxes or slideways for the pistons s , and the sides of the ring r are covered by ring-plates t , which inclose the operating mechanism of the pistons, and are slotted, so that the pistons may project in contact with the side plates, $b c$, of the case. The pistons s are fixed on the outer ends of arms u , that project from a central cross-head, v , the arms being packed where they pass through the ring r , (see Figs. 2 and 5,) and in the sides of pistons s there are fitted metal packings s' , which are forced outward in contact with plates $b c$ by spiral springs s^2 .

The cross-head v is slotted and contains a sliding box, w , into which enters the end of the fixed tapering shaft w' . This shaft w' is sustained in a box, a' , that is attached upon the spider c' , and extends into the hollow axle d contiguous to the cross-head v and slide w . The shaft w' is fitted into the box a' with a screw-thread, which permits its endwise adjustment, and a set-nut is applied for clamping the shaft in place. This construction permits adjustment of shaft w' to compensate for wear, the shaft w' , by its taper, spreading the box w . The end of box a' holds the slide w in place, and to allow of adjustment the holes through which the screws a^2 pass to hold the box a' are elongated, as shown in Fig. 10.

The position of the shaft w' is below the center of wheel B on a line drawn vertically through the said center. The shaft w' and the axis of wheel B being fixed, the rotation of the wheel causes the projection of the pistons s , their

path of rotation being an ellipse. This will be most clearly seen by reference to Figs. 6, 7, 8, wherein the horizontal dotted line D D passes through the center of wheel B and the center of slide w , and the line E through the center of shaft w' or the center of the steam-way.

In Fig. 6 the pistons are horizontal, projected at an equal distance at both sides of wheel B, and the central point between the two pistons is on the center of the wheel.

In Fig. 7 the wheel has made an eighth of a revolution, and the center point between the two pistons has moved to the right from the center of wheel A.

In Fig. 8 the wheel has made a quarter-revolution, bringing the pistons vertical, and the center point between them at the center of shaft w' . The figure thus described at the outer end of the pistons is that of an ellipse, the major diameter of which is on a line drawn horizontally through the center of shaft w' .

At the top of case A is fitted the steam-chest and valve-chamber C, containing a slide-valve, 25 q . The valve q is formed with a rack on its upper surface, which engages a pinion, e' , that is fixed on a shaft, j' , which extends through case C, and is fitted with a handle, whereby the valve may be moved to reverse the movement of the engine. The valve q is of a size to extend over the exhaust-port o and either port m or m' , and is recessed at the under side. By these means the steam, air, or water entering the case C by pipe g^2 is directed to either port m or m' , according to the direction the engine is to be turned.

In operation the steam, air, or water enter-

ing by the port m or m' acts with full force on the piston as soon as the piston reaches the end of groove n or n' , which is at the same moment that the opposite piston reaches the opposite groove n or n' , and the steam begins to exhaust by such groove. The engine may be used as a pump or blower, a separate motor being used in that case to drive the wheel.

Having thus described our invention, we claim as new and desire to secure by Letters Patent—

1. In rotary engines and pumps, the wheel B, fitted with pistons s , cross-head v , sliding box w , and hollow axle d , combined with case A, having an elliptical steamway, and the fixed axis w' , that enters the box w of the cross-head, substantially as shown and described.

2. In combination with the sliding box w , 55 cross-head v , pistons s , and wheel B, the tapering and threaded shaft w' and the box a' , fixed upon the frame of the engine and extending through the hollow axle of the wheel, substantially as described and shown.

3. In combination with the rotary wheel B, 60 having the hollow axle d , and fitted with sliding pistons s , cross-head v , and box w , the box a' , fixed adjustably upon the frame of the engine and projecting through the axle d to the head v , substantially as and for the purposes set forth.
